ATTORNEY

UNITED STATES PATENT OFFICE

DAVID R. REED, OF DALLAS, TEXAS, ASSIGNOR TO ONOR L. JONES, OF DALLAS, TEXAS

RUG-DISPLAY RACK

Application filed November 19, 1928. Serial No. 320,469.

This invention is related to racks or hang-
ers for the display of merchandise, more partic-
ularly racks for rugs.

The primary object of the invention is the
provision of a display rack for rugs of a size
which substantially cover the floor of a room
or the like. Rugs of standard sizes for this
purpose are somewhat heavy for easy han-
dling in display and the invention aims to
10 provide a swingable and adjustable rack on
which one or more rugs may be suspended or
hung for inspection.

Another feature of the rack is that it is of
comparatively small dimensions, occupying
15 little space and is inexpensive of manufac-
ture; and the rugs are fully disclosed by
swinging the rack from side to side.

The invention will be clearly understood by
a perusal of the following detailed descrip-
20 tion, taken in connection with the accom-
panying drawings forming a part of this
specification and wherein:

Figure 1 is a side elevational view of the
rack attached to the wall of a building,

25 Figure 2 is an end view of the rack,

Figure 3 is a top plan view, and

Figure 4 represents a detail view of one of
its rollers and adjacent parts.

Having a more detailed reference to the
30 drawings, 1 denotes a building wall or other
stable support to which the rack may be at-
tached. This may be accomplished by means
of the angle members 2 and 2', the latter one
being at the floor line, indicated at 3.

35 The rack comprises an upright rod 4,
spaced between and rigidly connected to an
angle bar 5 and a strip 6. As clearly shown
in Figure 1, both the rod 4 and strip 6 are
pivoted to the angle members 2 and 2' to per-
40 mit the rack to be swung from side to side in
displaying the rugs. The rod 4, angle bar 5,
strip 6 and members 2 and 2' comprise a
swingable frame upon which is mounted an
adjustable element upon which the rugs are
45 directly suspended or hung.

This element consists of a horizontally dis-
posed bar 7, with sharp projecting elements
7', the bar sufficiently strong and formed of
any suitable material, and reinforced by an
50 obliquely disposed supporting bar 8. The bar

7 and bar 8 are connected together at their
outer ends, at A.

To enable the rack element to adjustably
ride the rod 4, a roller 9 and a roller 10 are
provided. To support the roller 9, the inner
55 end of the bar 7 is forked and straddles the
rod 4, and spaced between the forks is seated
the roller 9. This enables the roller to bear
against one side of the rod 4 and the fork
maintains the roller in alined engagement
60 with the rod.

The roller 10 is disposed on the inner side
of the rod 4 and is seated between opposite
65 sides of a bracket 11 (see Figure 4). The
bracket is attached to the inner end of the ob-
liquely disposed bar 8 in such manner as to
allow the roller 10 to bear against the inner
side of the rod 4. Both rollers, however, may
be arranged otherwise than here shown in
70 enabling them to roll in opposite positions or
sides of the rod 4.

Referring to Figure 1, it will be observed
that the inner or free end 5' of the angle bar
5 is bent over and is recessed for the recep-
75 tion of the bar 7. This straddle-wise ar-
rangement maintains the bar 7 in alinement
with the angle bar 5 when the rack element is
at the top of the frame and prevents lateral
movement of the rack element and rugs.

The means for raising and lowering the
rack element is provided by an arrangement
of pulleys 12 and 13 and cord 14. In the
present structure, the cord has one end at-
tached to the angle bar 5 at the point 15 and
rides over the pulley 12 thence over and
around the pulley 13. The pulley 13 is
85 mounted in a support forming part of the
angle bar 5, and from this point the cord ex-
tends to a knob 16 in the wall or support 1,
to prevent the cord from slipping when the
rack element is in operative position.

In operation, the rugs are impaled on the
projections 7' one rug on each side of the bar
7 and the rack element is swung from side to
95 side to show the surfaces of the rugs. The
dotted line position in Figure 1 denotes the
lowermost position of the rack element and
at this position the rugs may be easily at-
tached to the rack. The cord 14 may then be
100

pulled and the rugs raised to position for inspection.

Obviously, changes and alterations are possible in the present structure, such modifications to come within the appended claims.

5 What is claimed is:

- 10 1. A display rack for rugs, comprising a vertical rod spaced between and rigidly connected to an angle bar and a strip, said strip and angle bar being pivoted to a stationary support; a horizontal bar carrying projecting elements for attaching the rugs to the bar, the inner portion of the horizontal bar having spaced parts to embrace the rod, a roller on the ends of the spaced parts, the roller adapted to ride along the rod to hold the bar thereupon; means for bracing the bar on the rod, means for raising and lowering the bar and means for stabilizing and holding 20 the bar in display position.
2. A display rack for rugs as set out in claim 1, said means for raising and lowering the bar comprising a pulley mounted upon said horizontal bar, a pulley mounted upon 25 said angle bar and a cord attached to the angle bar and connected to the pulleys; said bracing means comprising a bar connected to the outer end of the rug supporting bar, the inner end of the bracing bar encircling the 30 rod and carrying a roller and adapted to ride loosely upon the rod in supporting the rug supporting bar.

In testimony whereof I affix my signature.

DAVID R. REED.
